DESIGN FOR A STOKER

Bernard Morse Guthrie, Chicago, Ill., assignor to Fairbanks, Morse & Co., Chicago, Ill., a corporation of Illinois

Application October 26, 1939, Serial No. 87,873

Term of patent 7 years

To all whom it may concern:

Be it known that I, Bernard Morse Guthrie, a citizen of the United States, residing in the city of Chicago, county of Cook, and State of Illinois, have invented a new, original, and ornamental Design for a Stoker, of which the following is a specification, reference being had to the accompanying drawing, forming a part thereof.

In the drawing:

Fig. 1 is a perspective view of a stoker, showing the front and right hand sides thereof.

Fig. 2 is a similar perspective view, but showing the rear and left hand sides of the stoker.

The dominant features of my design reside in the portions shown in full lines.

I claim:

The ornamental design for a stoker, substantially as shown and described.

BERNARD MORSE GUTHRIE.
